UNITED STATES PATENT OFFICE

DAVID C. GARROWAY, OF BELMONT, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH AND CONTACT STRUCTURE THEREFOR

Application filed January 2, 1926. Serial No. 78,819.

This invention relates to electric switches and has for an object improvements in the construction of contact members therefor.

A common type of contact member comprises a tube into which the cooperating contact member, usually a rod, is moved to complete the circuit. The tube is split along its length to form a plurality of separate segments or shoes, and a coiled annular spring 5 encircles the segments to press them yieldingly against the rod.

When the switch is opened under heavy load it sometimes happens that the circuit-interrupting arc enters the space between two 15 adjacent segments and burns and severs the spring, so that good pressure contact cannot be made when the switch is again closed.

It is an object of this invention to provide a segmental contact member of the type above 20 set forth with spring-means to urge the segments against the cooperating contact rod, the spring-means being so arranged that the circuit-interrupting arc cannot readily gain access thereto.

25 A further object is the provision of a split contact member so arranged that each segment thereof is independently positively connected electrically in the circuit through the switch.

30 A further object of the invention is the provision of a bell-type contact member and supporting means therefor so arranged that the contact member is self-centering on the cooperating contact rod, thereby to facilitate 35 engagement between the two regardless of small departures from absolute alignment.

A further object is generally to improve the construction and operation of electric switches and circuit interrupters.

40 Certain features of this invention are disclosed in my co-pending joint application with Chester D. Ainsworth filed January 2, 1926, Serial No. 78,818.

Fig. 1 is a more or less diagrammatic representation of the separable contact member of

an electric switch in which this invention is incorporated.

Fig. 2 is a side elevation, partly in section, of the stationary contact structure of Fig. 1, in which the invention is embodied.

Fig. 3 is a plan view of the contact structure of Fig. 2, the supporting bracket being broken away.

Fig. 4 is a section along line 4—4 of Fig. 2.

Fig. 5 is a side elevation of one of the segments of the bell contact member.

As shown in Fig. 1 the electric switch embodying the invention includes the stationary switch members 10 and the movable switch member 12. The movable switch member includes a cylindrical contact rod 14 which is extended vertically upward from a supporting bar 16 and is adapted to enter a stationary-supported tubular contact member or bell 18 carried by a stationary switch member.

The contact bell includes a metal tube which has an internal vertical passage 20 extended from end to end thereof in which the contact rod 14 is adapted to be received and to make contact. The passage has an outwardly flared lower entrance 22 which facilitates entry of the contact rod into the bell and also serves to effect the lateral shifting of the bell into alignment with the rod, if the bell is initially displaced from such alignment. The upper end of said passage is also provided with an outwardly flaring end 24.

Said bell is supported in a bracket 26 which is fixed to and is in electrical connection with a stationary switch member 10. Said bracket is formed or provided with an approximately circular head 28 in which said bell is received. Said head is formed with a circular recess 30 in its top face and a wall 32 which closes the bottom of the recess. Said wall is formed with an aperture 34 therein through which the contact bell is extended. A cover plate 36 is disposed on said head to cover the top of said recess and is provided with an aper-

ture 38 through which said bell is extended. Said cover plate is secured removably in the aforesaid relation by bolts 40 which extend through said cover plate and are screw-threaded into said head. The contact bell is provided with a radially-outstanding annular flange 42 intermediate its ends, which flange is disposed within said recess 30 and is adapted to rest upon the bottom wall 32. Said recess 30 is arranged to be substantially greater in diameter than the diameter of said flange 42 so that the bell can move freely, or float, therein whereby to be self-aligning with the movable contact member. The height of said recess, however, is arranged to be but little greater than the thickness of the flange, so that the bell will be restrained against any material amount of vertical movement.

Said contact bell is slit radially from end to end in a manner to form a plurality of separate segments or shoes 44, three shoes being here shown. Means including spring elements are provided to urge said shoes inwardly toward their common center and said spring elements are arranged to be concealed and shielded against the circuit-interrupting arc. Said means includes a ring 46 which is disposed within said recess 30 and encircles the flange 42 of said contact bell. Said ring is provided with a plurality of radially inwardly directed pins 48 which have screw-threaded outer ends 50 which are screw threaded removably into said ring. Said pins are received in radially inwardly directed recesses 52 formed in the shoes 44. As here shown, each shoe is provided with two recesses in which pins are disposed. Springs 54 encircle said pins and are received in enlargements 56 of said recesses and are approximately completely enclosed within said recesses. The inner ends of said springs bear against shoulders 60 of said shoes and the outer ends bear against said ring 46. The arrangement is such that said springs tends constantly to urge said shoes inwardly toward the common center and thereby into firm contact with the movable contact rod 14 while the pins 48 serve to guide said shoes during such movement. The springs are practically entirely enclosed within the shoes and thereby occupy positions inaccessible to the circuit-interrupting arc. The bottom wall 32 of the recess further shields said springs against contact with the circuit-interrupting arc and the hot gases resulting therefrom.

Said cover plate 36 is provided with an upwardly extended wall 62 which is terminated at its upper end in an inwardly-directed flange 64 whereby to form an enclosure or housing 66 about the upper portion of the contact bell. Means are disposed within said enclosure by which each contact shoe 44 is independently and positively electrically connected with the bracket 26. Said means includes a plurality of flexible leads 68, two

being associated with each shoe. Said leads are secured to and connected electrically with the shoes by means of screws 70. Slots 72 are formed in the flange 64 and upper portion of the wall 62 of the cover plate adjacent each shoe and the leads are extended in pairs outwardly through said slots. The outer ends of said pairs of leads are reflexed away from each other and against the wall 62, in which position they are secured by screws 74. This arrangement permits the bell to float within its supporting bracket, and permits independent movement of each shoe, while maintaining positive electrical connection between the shoes and the bracket.

I claim:

1. A contact structure for electric switches including a supporting housing open at both ends, and a tubular contact member having a contact-receiving passage extended therethrough which is open at both ends received in and having a floating connection with said housing and extended through both ends thereof for a substantial distance away from said housing both above and below it, whereby the arc is drawn remote from the housing.

2. In an electric switch, a fixed switch terminal, a contact structure therefor including a conducting arm having attaching means at one end connected electrically and mechanically with said terminal and having a housing at the other end provided with an aperture therethrough, and a tubular contact member received loosely in said aperture in angular relation with said arm and extended both above and below said housing and having an outstanding flange which is laterally loose in said housing, and means electrically connecting said contact member and housing loosely.

3. An electric switch having an upper tubular contact member the passage therethrough being freely open so that arc gases can pass freely upwardly therethrough, a lower contact member comprising a rod movable into and out of the passage in said tubular contact member, said tubular contact member including a plurality of contact segments having resilient supporting means therefor, said resilient supporting means being out of the path of the rising circuit interrupting arc gases through said passage, and means enclosing said resilient supporting means which prevents access of arc gases thereto through the spaces between the segments of said contact member.

4. An electric switch having an upper tubular contact member the passage therethrough being freely open so that arc gases can pass freely upwardly therethrough, a lower contact member comprising a rod movable into and out of the passage in said tubular contact member, said tubular contact member including a plurality of contact segments, each having resilient supporting means therefor,

each resilient means characterized by lying entirely within the circumferential extent of the segments, and means cooperating with said segments to shield said resilient supporting means against any deleterious contact with the rising arc gases which may pass through the spaces between adjacent segments of said contact member.

In testimony whereof, I have signed my name to this specification.

DAVID C. GARROWAY.
